UNITED STATES PATENT OFFICE.

WILLIAM T. MILLIGAN, OF BOSTON, MASSACHUSETTS, ASSIGNOR TO THE BRUNSWICK SHIP'S BERTH COMPANY, OF CONNECTICUT.

AUTOMATIC SHIP'S BERTH.

SPECIFICATION forming part of Letters Patent No. 277,321, dated May 8, 1883.

Application filed October 23, 1882. (No model.)

To all whom it may concern:

Be it known that I, WILLIAM T. MILLIGAN, of Boston, in the county of Suffolk and State of Massachusetts, have invented a new and useful Improvement in Automatic Ship-Berths, of which the following is a specification.

So far as I know, no "self-leveling berth," so called, has heretofore been built which must not be hung, say, from two to three and one-half inches from the side of the state-room next which it lies, in order that it may not strike the wall as the ship rolls. This has been a great objection to such berths, for this space must be taken off the size of the state-room, and in the state-rooms of an ocean steamer, for example, such a waste of room is a serious matter.

The purpose of the main portion of my invention is to enable the berth to be hung nearer the side wall of the state-room than has hitherto been possible; and it consists in a berth the longitudinal axis of which is adapted to move laterally (with respect to the walls of the state-room) as the berth swings, in an opposite direction to that in which the berth swings.

My invention also consists in the combination of a swinging berth with a governor adapted to receive its motion from the rolling of the ship, and so control the berth's movements that it will swing from side to side in substantial unison with the regular roll of the ship, and will not be materially affected by any sudden and irregular shock given the ship by a heavy sea, nor by any movement of the occupant of the berth.

It also consists in a berth adapted to swing upon a transverse axis, and provided with two sets of springs, placed one set on each side of said axis, and of such construction and arrangement that any weight tending to contract one set of springs will tend also to contract the other set.

It also consists in a berth hung by flexible supports over suitable lateral pivots, and provided with suitable mechanism for adjusting the head and foot of the berth to the weight of the occupant, so that when occupied and at rest it may hang substantially level, or at any angle desired, irrespective of the comparative weight of the occupant's body and legs.

It also consists in certain details of construction, all fully described below.

In the drawings, Figure 1 is a cross-section of a berth embodying my invention, showing the governing mechanism for use at the head of the berth, the weight G^2 being omitted, Fig. 2 being a section on line xx , Fig. 1. Fig. 3 is a cross-section showing the locking mechanism at the foot of the berth, the weight G^2 being omitted, and Fig. 4 is a section on line yy of Fig. 3. Fig. 5 is a longitudinal vertical section through the middle of the berth, the views of the ends of the berth corresponding with the views in Figs. 2 and 4, respectively, except that a portion of the governing and locking mechanism is omitted, as is also a portion of the frame H , so that the position of the lateral mechanism may be seen. The other figures will be referred to below.

It is obvious that the main feature of my invention may be accomplished in a variety of ways by means of suitable cams or springs, &c.; but the mode which now seems to me the best for carrying it out is that shown in the drawings.

A A' are two circular metallic heads of a diameter of, say, twenty-six inches—two inches or so larger than the width of the berth. Each head is provided with a pair of sockets, B B', into which fit the ends of the beams B' B'. These beams are for the purpose of supporting the berth, and the sockets B B' should be so arranged as to bring the center of gravity of the berth, when occupied, as low as possible. Each head is also provided with a rim, a , projecting from its back, say, one-half an inch, and of sufficient thickness to support the weight of the berth and its occupant. This rim rests upon a series of disks, $a' a^2 a^3 a^4$, which in turn rest upon the elliptical track C, secured to the bulk-head. The shortest diameter of this elliptical track is best about two and one-half inches less than its longest diameter, and its longest diameter about two and one-half inches less than the diameter of the head. About fifty degrees of the lower portion of this track are unnecessary, and may be dispensed with. The disks are seven in number, the largest one, a' , being best made of sufficient diameter to hold

the head, so that normally its horizontal diameter shall be in the same horizontal plane with the longest diameter of the elliptical track C. The other disks are made in pairs of different diameters, so as to divide as equally as possible the weight upon the track, as shown. These disks are best made without axles, and unconnected in any way. This portion of my invention operates as follows: As the ship rolls the berth swings or rotates (with respect to the walls of the state-room) upon the disks a' , a^2 , a^3 , and a^4 , and the center of each head will move laterally in a straight line directly opposite to the direction in which the berth swings a distance depending upon the proportionate length of the diameters of the ellipse, and consequently the size of the friction-rollers. By properly proportioning the parts a berth which, if swinging upon a fixed axis, would swing, say, two and one-half inches on each side of a perpendicular dropped through its center when at rest, will swing only one and one-quarter inch each side of the said line, the lateral movement of the axis serving to compensate for the remaining one and one-quarter inch. Consequently such a berth need only be hung, say, one and one-half inch from the state-room wall, instead of two and three-quarter inches. This will be understood from Fig. 10, in which, however, the berth is represented as remaining horizontal, and the state-room wall L and the elliptical track C are out of perpendicular in consequence. The lower half of the circumference of each piece A A' is provided with ratchet-teeth, half pointing one way and half the other, as shown.

It is very desirable that the berth shall not swing with every little motion of the ship, but shall only conform with its regular roll. To insure such steadiness I use a governor which shall be operated by the rolling of the ship, and shall restrict the motion of the berth a sufficient degree to keep it from swinging with every blow given the ship by the waves.

The best form of governor now known to me is shown in Fig. 1. It consists of a metallic semicircle, D, of the same diameter as the head A, upon the circular edge of which are teeth equal in number to the number of teeth upon the lower half of the head A. The head A and piece D are connected by means of two pawl-levers, d, which are held against both the piece D and the head A by means of spring d', and arranged in such a way that one pawl will engage with the ratchet A while the other pawl is disengaged. The piece D is pivoted to the bulk-head of the state-room at D', and connected with it and swung upon the same pivots is a weight, D², of sufficient heaviness to counterbalance it and give it a positive motion whenever the ship rolls. The teeth upon the piece D are equiangular, and the lower end of each pawl is provided with a friction-roller, and consequently whenever the ship rolls the weight D² moves the piece D, and the roller upon each pawl-lever d in turn rides up upon

and over one of the teeth on the piece D and disengages its other end from a tooth upon the head A; but as soon as each roller has passed over one tooth one of the springs d' will drag its pawl-lever into the hollow between that tooth and the next one, and will cause the other end of the lever to engage with the next tooth in the head A. It will be seen that the berth can move only the distance corresponding to one tooth at a time; and, moreover, the distance which the weight travels must equal a certain amount before it will allow the berth to move at all. Consequently the berth will not swing with every shock which the ship receives, but only, under ordinary circumstances, with its regular roll. This form of escapement seems to me the best and simplest for my purpose, though others may be used to transmit motion from the governor to the berth. 85

The foot of the berth is provided with a locking device to enable the occupant of the berth to lock it whenever he desires to prevent its rotation. This device consists of a pair of pawl-levers, E, controlled by springs e, and connected by means of a series of rods and levers, e', with a handle, e², within reach of the occupant of the berth, so that by moving the handle the berth may be locked or unlocked, as the case may be. The handle should be arranged as shown, so that it will be over the occupant's body when the berth is unlocked, and very much in the way, so much so that the occupant cannot help seeing it when he starts to leave his berth; nor can he leave his berth except with much trouble, without pulling the handle out of the way, and so locking the berth. When he wishes to lock the berth he pulls the handle toward him and latches it by means of the latch e³, as will be understood from Figs. 3, 11, and 12, this motion moving the levers and rods so as to force the pawls against the ratchet-teeth on head A'. 100

The beams B' B' are for the purpose of supporting the berth proper, and each is provided with a friction-pulley, b, over which passes a wire rope, b', by which the berth is hung. 110

Each side of the berth is provided with a link, b², pivoted at its lower end to the frame F and at its upper end to the beam B'. Its 115 purpose is to prevent the berth from falling in case one of the supporting-ropes should break. The hole by means of which it is pivoted to the beam B' should be large enough to prevent the link from restricting in any way the 120 movements of the berth when the rope is intact.

The berth proper is composed of a rectangular frame of proper size, to which a suitable mattress or support for the bedding is attached. 125 The mattress shown in the drawings I believe to be of my own invention, and I propose to make an application for Letters Patent of the United States therefor in due time.

To each beam B' are attached two helical springs, G G'. These springs are coiled in the same direction, but their helices are so attached 130

to the beam that the outer or straight part of the spring G at the head of the berth starts from the upper part of the helix, while the corresponding part of the spring G' at the foot of the berth starts from the lower part of the helix. The straight portions of these springs may be attached to the frame F in any convenient way. A person's body being heavier than his legs, he will naturally depress the head of a berth, pivoted as shown, more than the foot. When, however, the springs are arranged as shown, as one pair of springs is on each side of the transverse axis of the berth, the weight at the head of the berth will not only be counterbalanced by the springs G at the head, but also by the weight of his legs and the springs G' at the foot of the berth. By some such arrangement as this, springs of substantially equal tension can be used to support the different weights of the upper and lower parts of the human body. The springs, of course, need not be helical, though I believe that to be the most convenient form of spring for my purpose; and it is evident that if they are not helical they need only be so far attached to both parts of the berth as to be compressed when a surplus of weight is applied to the head of the berth. In any case they had best be counterbalanced by one or more weights, G², of, say, ten pounds or so, sufficiently heavy to steady the berth when it is not in use.

It is desirable that a berth hung by a flexible support and swinging upon a transverse axis should be adjustable, so that it may be made to answer equally well for different persons, the weight of whose bodies and legs is in a different proportion. If such a berth has no springs such as the springs G G', the desired end may be gained by hanging the berth from pivots, which may be moved in slots in the beams B' the desired distance and clamped, so that the relative lengths of the ropes supporting the head and foot of the berth (if ropes be used) may be changed at will.

Berths have heretofore been hung by inflexible straps or rods; but in such cases any unusual strain may cause the rods to break or bend, and in case any mode is provided for the adjustment of the berth—by changing the point of suspension, for example—such adjusting mechanism will become useless. When, however, such springs as are shown in the drawings are used, a convenient mode of adjustment is as follows: The helical end of each spring is attached to an arbor, g, which passes through the beam B', and through a ratchet, g', provided with two sets of teeth, one set upon one half of its circumference, the other set upon the other half. The outer end of the arbor is squared, so as to be turned by a wrench. The ratchet g' is provided with two pawls, g², one operating upon each set of teeth. This arrangement I deem advisable, so as to prevent any change in the tension of the springs owing to any unusual or sudden strain being brought to bear upon them. When it is de-

sired to adjust the head of the berth for a heavy person the springs G would be tightened and the springs G' loosened, so as to cause the head of the berth to be raised and its foot lowered at the same time. Its head will then sustain a greater weight than before without throwing the berth out of level. This arrangement of springs and flexible suspension has another advantage, in that when the berth swings in its transverse axis, it being suspended from the fixed points and its motions being partly controlled by the springs G G', whenever the berth swings on its transverse axis the ropes will be caused to give a little over the points of suspension, so as to shorten the radius of that end of the berth which is approaching the ceiling of the state-room, and consequently the berth will rotate on its transverse axis in less space than it otherwise would.

The springs G G' and ropes b' may be attached to the sides of the berth F in any desired way. I prefer, however, to provide each side F of the frame with two plates, b³, to each of which is attached a roller, b⁴, which is of sufficient diameter to bear upon one of the beams B', and serves to steady the berth between the beams and enable it to oscillate on its transverse axis without friction. To each plate b³, I attach one end of a spring, G G', and of a rope, b'. The sides of the berth are provided with a frame or shield, H, which is best made in the form of a rectangle of substantially the size of and attached to the frame F, so that it will move with it. It should be sufficiently high to cover all the side mechanism, and as it moves with the mattress-frame F, instead of being attached to the beam B', it will prevent the occupant of the berth from hindering its free oscillation on its transverse axis, as he might otherwise by his position or his arrangement of the bed-clothes.

The parts of the berth are best made of metal, either cast-iron or composition, except the beams B' B', the inner frame, H, and berth-frame F, which may be made of wood. The springs G G' are best made of steel one-fourth of an inch square in cross-section. Such a spring requires but slight tightening to materially increase its tension—so little, in fact, that where the ratchet is, say, two inches in diameter and provided with, say, twelve teeth on a side, the change in the position of the ratchet on each spring one tooth will change the capacity of the head of the berth about ten pounds.

What I claim as my invention is—

1. An automatic ship's berth adapted to rotate around its longitudinal axial line, and provided with mechanism, substantially as above described, whereby a lateral curvilinear motion is given to its axis of oscillation, all as and for the purposes set forth.

2. In an automatic ship's berth, the combination of the heads A A', suitably connected together, and each provided with a rim, a, projecting from its upper edge, adapted to sup-

port its head upon a series of disks resting and adapted to be rotated upon a suitable elliptical track, C, attached to a stationary support, with said disks and tracks, all as and for the purposes set forth.

3. An automatic ship's berth adapted to rotate about its longitudinal axial line, and provided with proper means of pivotal support, in combination with devices, substantially as described, whereby the relative motions of the ship and berth are controlled and the rate of such relative motions regulated, all substantially as set forth.

4. In an automatic ship's berth, the combination of the head A, provided with suitable ratchet-teeth upon its lower periphery and pivoted to suitable supporting mechanism, and the governor D D², hung from a suitable support upon an independent axis, and provided with suitable escapement mechanism, substantially as shown, operating, in connection with the governor and the head A, to control the rotations of the berth, all as set forth.

5. In an automatic ship's berth, the locking mechanism above described, consisting of the head A', suitably supported, and provided with suitable ratchet-teeth upon its lower periphery, and one or more pawls suitably pivoted to a fixed support, connected together and adapted to be operated by means of levers to interlock with said ratchet-teeth, all substantially as and for the purposes set forth.

6. An automatic ship's berth hung from pivots attached to lateral supports and provided with two sets of springs, one set at the head of the berth and the other set at the foot of the berth, arranged and attached to the berth and its said lateral supports, substantially as

described, the set at the foot of the berth adapted to act with the set at the head of the berth to counterbalance any otherwise unbalanced weight at the head of the berth, as and for the purposes set forth.

7. The berth above described, adapted to swing upon a transverse axis, and provided with suitable springs upon each side of said axis, connecting said berth with the frame, to which it is laterally pivoted, and suitable weights, whereby the berth may be steadied against any sudden vertical jar, all substantially as and for the purposes set forth.

8. An automatic ship's berth hung at each side from a lateral support by a rope passing over a pulley attached to one of said lateral supports, upon which ropes said berth is adapted to rotate about said pulleys, and provided with springs attached to said lateral supports and said berth, substantially as described, whereby as said berth swings said ropes are caused to travel over said pulleys, and the position of the transverse axis of said berth is caused to move with respect to the head and foot of the berth, substantially as and for the purposes set forth.

9. In an automatic ship's berth adapted to swing around a transverse axis, the mechanism above described for adjusting the berth around said axis, consisting of the springs G G', attached at their outer ends to the supporting-beams B' B', and each provided with an arbor, g, to which it is attached, and ratchet g' and pawls g², substantially as described.

WM. T. MILLIGAN.
